UNITED STATES PATENT OFFICE

WILLIAM H. RIFE, OF CHICAGO, ILLINOIS

DUPLEX ENVELOPE

Application filed September 13, 1928. Serial No. 305,670.

This invention relates to an improved duplex envelope of a type designed to provide separate inner compartments within the body of an envelope, each compartment being adapted to receive mail matter of a classification different from that received by the other compartment.

Another object of my invention is to provide an envelope of a type particularly adapted to effect an economy of time, labor and material by a simplified construction.

Additional objects and advantages of the method and construction will appear more fully in the hereinafter specification, when taken in connection with the accompanying drawings, in which:

Fig. 1 is an inside plan view of my envelope before sealing;

Fig. 2 is a fragmentary front view of the construction shown in Fig. 1;

Fig. 3 is an elevation of the reverse side of the envelope;

Fig. 4 is a transverse section taken on line 4—4 of Fig. 3;

Fig. 5 is a longitudinal section taken on line 5—5 of Fig. 3;

Fig. 6 is a fragmentary longitudinal section taken on line 6—6 of Fig. 3, the flaps shown in the right hand side of Fig. 3 being tucked within their respective compartments;

Fig. 7 is a fragmentary plan view of a modified form of the construction shown in Fig. 1, whereby inspection of the flap of the smaller container may be made when the larger flap is sealed thereover; and

Fig. 8 is a fragmentary view of the construction shown in Fig. 7, when folded to inclose and forward mail matter.

In the drawings, 11 is the body portion of a duplex envelope embodying my invention, having top and bottom flaps 12 and 13 respectively, a permanent closure flap 14 and a sealing flap 15. Gummed or otherwise suitably secured to the top flap 12 of the body portion of the envelope is a sheet of paper stock 16 having a flap 17, with a gummed body portion 18, the sheet 16 in this manner providing a small compartment 19 which may be used as an enclosure for first class

mail matter, if desired, when the flap 17 is sealed.

In the construction shown in Figs. 7 and 8, 15 designates a cut-away portion on the flap 15. When the gummed portion 22 is folded over, the flap 15 may be sealed thereby over the smaller flap 17 in a manner to disclose the postage stamp on the latter, and whether or not the smaller flap is sealed for first class mail matter or merely tucked in the small compartment 19.

It will be observed that by the construction shown I am enabled to effect a substantial saving of paper, since the flap 12 serves as the back wall of the small compartment 19 and also as one of the closure flaps for the back of the larger envelope. I have found it desirable at times in the manufacture of the construction shown, to first cut the paper stock into the shape displayed in Fig. 1 and then to apply the gum to the borders, to be followed by the gumming on of the sheet 16, these steps being expeditiously accomplished by machine process.

It is to be understood that slight variations and changes may be made in the construction shown without departing from the spirit or sacrificing any of the advantages of the invention described and illustrated; hence the invention is not to be confined to the details literally as set forth, as I desire to avail myself of such variations and embodiments as fairly lie within the scope of the appended claims.

What I claim as new and desire to secure by Letters Patent is:

1. A duplex envelope comprising a body portion having top, bottom and side flaps, one of said side flaps providing a permanent closure for said envelope when affixed to the folded and glued top and bottom flaps, said top flap having a single sheet of paper glued to its inner side to provide a small receptacle between said paper sheet and said top flap, said small receptacle being within the large compartment provided by the body portion and the co-acting top, bottom and side flaps, and an individual sealing flap for said small receptacle and said large compartment.

2. A duplex envelope comprising a body

portion having top, bottom and side flaps adapted to fold over and provide a compartment for receiving mail matter, a single sheet of paper glued to the inner surface of said top flap to form a small compartment, said single sheet of paper also having a sealing flap projecting out of said compartment and adapted optionally to be tucked within said small compartment and to be glued on the outside portion of said outer flap to provide a seal for first class mail matter, and a flap on said body portion adapted to be optionally tucked into the larger compartment or to be sealed over on the outside portions of said top and bottom flaps whereby both the large and smaller compartments may be sealed against inspection if desired.

3. A duplex envelope formed of a sheet of paper cut to provide top, bottom and side flaps when folded, a second sheet of paper gummed to the inner surface of one of said flaps to form a small compartment, said first mentioned sheet of paper providing a large compartment when the top, bottom and side flaps are folded and gummed, a flap on said second sheet of paper serving as a seal for said small compartment, an additional flap on the first mentioned sheet of paper for closing both of said compartments, said additional flap having a cut away portion whereby when the additional flap is sealed over the flap on the said second sheet of paper, a space on said last mentioned flap will be disclosed to indicate the postage thereon and its position on the inside or outside of said small compartment.

4. A duplex envelope formed of a blank cut to provide top, bottom and side flaps, one of said flaps having a comparatively thin sheet of paper affixed to the inner side thereof to form an inner compartment, said inner compartment being contained in the larger compartment provided by the folding of said top, bottom and side flaps of said blank, one of said side flaps having a cut away portion providing a means for disclosing a flap on the said sheet of paper when folded thereover.

5. A duplex envelope formed of a sheet of paper cut to provide top, bottom and side flaps when folded, a second sheet of thinner paper affixed to the inner surface of one of said flaps to form a small inner compartment within the larger compartment provided by the folding of said top, bottom and side flaps, one of said side flaps having a cut away portion providing a means of determining whether or not the small compartment has been sealed and whether postage has been provided on the small sealing flap for said small compartment.

In testimony whereof I have signed my name to this specification.

WILLIAM H. RIFE,
